UNITED STATES PATENT OFFICE.

NILS D. LEVIN, OF COLUMBUS, OHIO, ASSIGNOR TO THE JEFFERY MANUFACTURING COMPANY, OF COLUMBUS, OHIO, A CORPORATION OF OHIO.

METHOD AND MACHINE FOR LOADING COAL.

Application filed November 27, 1920, Serial No. 426,829. Renewed March 10, 1927.

The present invention relates to certain new and useful improvements in method and machines for loading coal and particularly to a machine adapted to use in the rooms 5 of a mine and the method of its operation for gathering the broken down coal from the floor of the mine and expeditiously and conveniently loading the same into cars for transportation from the mine.

10 The especial object of this invention is to provide a portable loading conveyor with improved means for gathering the coal from the floor of the mine onto the receiving end of said conveyor.

15 A further object is to provide apparatus of the class referred to adapted to be conveniently transferred from one working place to another.

A further object is to provide apparatus 20 of the class described having improved means for adjusting the position of the pit cars relative to the loading apparatus during the process of loading coal.

A further object is to provide a method 25 of operation whereby the devices above referred to may conveniently and effectively gather the broken coal from the floor of the mine and load it into suitably positioned cars for transportation from the mine.

30 These and other objects will appear in the following specification reference being had to the accompanying drawings of which

Fig. 1 is a perspective view of the preferred apparatus for carrying into operation 35 the method of loading hereinafter set forth.

Fig. 2 is a side elevation of the apparatus illustrated in Fig. 1 showing the parts adjusted to a position for traveling from one working place to another.

40 Fig. 3 is a side elevation of the apparatus illustrated in Fig. 1 when adjusted to operating position.

Fig. 4 is a cross section along the line IV—IV of Fig. 3.

45 Fig. 5 is a plan view of the truck element with the loading apparatus removed.

Fig. 6 is a diagrammatic plan view of the power elements of the machine.

50 Fig. 7 is a cross section taken along the line VII—VII of Fig. 3.

Fig. 8 is a fragmentary sectional view taken along the longitudinal central vertical plane of the conveyor at its forward end.

Fig. 9 is a section taken along the line 55 IX—IX of Fig. 3.

Like numerals refer to similar parts in the several figures.

The preferred apparatus for carrying into practice my improved method of loading coal 60 comprises, primarily, a conveyor of the well known chain and scraper type, having a horizontal receiving portion adapted to rest upon the floor of the mine during the loading operation, an upwardly and rearwardly 65 inclined central part, and a horizontal part adapted to extend above a conveniently placed car to deliver material thereto, a supporting truck adapted to facilitate the positioning of said conveyor for loading coal, 70 and for moving it from place to place, and certain auxiliary devices adapted and arranged to co-operate with the above described conveyor to gather material from the floor of the mine and distribute it in the 75 car for transportation from the mine.

The conveyor element consists of an elongated trough composed of the side plates 1 and the bottom plate 2 along which travel two endless chains 3 which are joined together at spaced intervals by the scraper 80 gated trough composed of the side plates 1 are angle bars 5 the flanges of which extend above the chains 3 to shield them from contact with the material traveling along the 85 trough. Other longitudinal angle bars 6 are fixed to the side plates 1 and to these are attached the bottom plate 7 which serves as a slide way for the return strand of the conveyor chains 3 and scrapers 4. Extending transversely of the conveyor structure at its rearward end is a head shaft 8 around which passes the conveyor chains 3. The shaft 8 is supported in journal bearings 9 adapted to adjustment longitudinally of the 90 conveyor to regulate the tension of the chains 3 in the manner common in conveyor practice. At the lower, or receiving, end of the conveyor the chains 3 pass around a stationary cross bar 10 to which is attached 95 100

- two guide bars 11 adapted to engage the rollers of the chains 3 to guide them from the lower to the upper run of the conveyor. Attached to the side plates 1 of the inclined 5 and the upper horizontal portions of the conveyor trough, by means of the straps 12, are flaring side plates 13 which serve to prevent the overflow of material along the sides of the conveyor trough.
- 10 To facilitate the movement of coal from the mine floor to the lower horizontal part of the conveyor, I have provided an inclined plane over which the coal may be moved in a manner which will hereinafter appear.
- 15 This inclined plane comprises a steel plate 14 which is reinforced by stiffening bars 15 connected by the hinges 16 with the lugs 17 adapted to engage the sockets 18 attached to the side plates 1 at either side of the conveyor frame. The plate 14 may thus be positioned, as shown in Figs. 1 and 7, with its free edge engaging the mine floor during the operation of loading, or it may be folded over upon the conveyor, as illustrated in
- 20 Fig. 2, to be out of the way while the machine is traveling along the mine tracks. I have provided an extension plate 19 adapted to form a continuation of the plate 13 at the side of the machine opposite the inclined
- 25 plane 14 to prevent the coal from over flowing along the lower horizontal portion of the conveyor. The plate 19 is provided with stiffening bars 20 the lower ends of which project downwardly to engage the sockets 30 18 to hold said plate in position. By this arrangement the extension side plate 19 and the inclined plane plate 14 may be attached at either side of the conveyor to adapt the machine to gather material from either side
- 35 of the mine working.
- Attached to the conveyor trough, equidistant from its ends, is a structural framework 21 forming a housing for the power elements of the machine, the side sills 22 of which
- 40 serve as a supporting base for the conveyor. Mounted within the housing 21 is an electric motor 23 the armature pinion 24 of which engages the spur gear 25 mounted upon the cross shaft 26 and connectible thereto by a
- 45 friction clutch 27 of the well known multiple disk type. The clutch 27 is provided with a controlling hand wheel 28 by which the friction elements may be readily engaged and disengaged in the manner well under-
- 50 stood in the art. Attached to the shaft 26 is a pinion 29 which engages a spur gear 30 fixed to a second shaft 31. The shafts 26 and 31 are journaled in bearings 32 and 33 formed in the extending arms 34 of the motor casing. Attached to the shaft 31, between the bearings 33, is a sprocket wheel 35 which is connected by a chain 36 with a similar sprocket wheel 37 attached to the cross shaft 38. To the projecting ends of
- 55 the shaft 38 are fixed two rope winding

winches 39 for a purpose which will hereinafter appear. The shaft 38 is also connected to the conveyor driving shaft 40 through the spur gears 41 and 42, and these shafts are supported in the bearings 43 and 44 secured to the structural steel frame work of the machine. To the driving shaft 40 are fixed two sprocket wheels 45 the rims of which project through convenient slots in the bottom plate 7 and engage the chains 3 to drive them. The bottom plate 7 is curved downwardly at 46 to form loops in the chains 3 to afford a sufficient contact with the sprocket wheels 45 to cause them to satisfactorily drive said chains. In order that the movement of the conveyor chains 3 and scrapers 5 may be controlled independently of the other elements of the machine I have interposed a clutch 42' between the gear 42 and the shaft 40, and this clutch is controlled by an operating lever 42" positioned convenient to the hand of the operator. As the details of these clutch elements form no part in the present invention and are well understood in the art, more complete description is not thought to be required at this time.

47 is a conductor cable which extends from the motor 23 to a suitable controlling switch 48, and thence to a receptacle 49 connectible with suitable flexible conductor cable through which current may be received from any convenient source of electrical supply. The conveyor member as above described, constitutes a self-contained structure, which when used in conjunction with the supporting truck to be hereinafter described, may be easily positioned with its receiving portion in convenient relation to the material to be loaded while its delivery end is above a car adapted to receive said material for transportation from the mine.

The supporting truck comprises a main frame formed of longitudinally extending side sills 50 which are rigidly joined together by cross members 51. Bolted to the side sills 50 are journal bearings 52 in which are mounted the truck axles 53 and 54. To the truck axles 53 and 54 are attached traction wheels 55 and 56 upon which the truck is supported on the rails 57 of the mine tracks. Positioned between the side sills 50 is a rectangular supplemental frame 58 to which is bolted the journal bearings 59 journaled upon the forward truck axle 53 constituting a hinge support for the forward end of the supplemental frame 58. The rearward end of the supplemental frame 58 is adapted to engage the rearward cross member 51, or to be elevated upon a block 60 interposed between it and the side sills 50 to effect the vertical adjustment of the rearward end of the conveyor. Supported in apertures of the upwardly extending flanges 61 of the supplemental frame 58 is a hinge

- rod 62 upon which is pivotally supported two bearing castings 63 which are secured to a flat plate 64 adapted to engage the side sills 22 of the conveyor housing. The plate 64 is provided with an aperture 65 through which projects a pivot pin 66 extending downwardly from the conveyor, and which serves to prevent lateral displacement of the conveyor while permitting it to be angularly adjusted 10 relative to the longitudinal lines of the truck preparatory to the loading operation. The pivot pin 66 is fitted with a nut arranged to engage the under side of the plate 64 to prevent its accidental withdrawal from the aperture 65. By lifting the rearward end of the conveyor the operator can rock the supplemental frame 58 about the axle 53 to permit the insertion of the block 60 beneath the supplemental frame 58 thereby 15 holding the rearward end of the conveyor in the desired relation with the car 67 during the operation of loading coal as shown in Fig. 3, and by pressing downwardly on the conveyor he may rock the side sills 22 about 20 the hinge rod 62 to permit the positioning of the block 60 between the supplemental frame 58 and the side sills 22 to hold the forward end of the conveyor clear of the track rails 57 during the movement of the 25 machine from one working place to another, as illustrated in Fig. 2. It will be seen that this arrangement of support, that is, the truck, conveyor frame, and the intermediate supplemental frame which connects them 30 pivotally, as described, forms what may be termed a "lazy tong" connection which permits vertical adjustment and tilting of the parts, and, by reason of the vertically disposed pivot connection between the conveyor 35 frame and the intermediate supplemental frame, angular adjustment of the conveyor frame in horizontal planes. The truck axles 53 and 54 are connected together by a suitable sprocket chain 68, and the forward axle 40 53 is fitted with a sprocket wheel 69 adapted to be connected through the chain 70 with the sprocket wheel 71 by a chain 70 which may be removed during the loading operation and replaced when the machine is to be 45 moved from one working place to another. The wheel 71 is rotatably mounted upon the projecting end of the cross shaft 31, and a clutch member 72 splined to the shaft 31 is arranged to connect the sprocket wheel 71 50 with the shaft 31 so that the power of the motor 23 may be transmitted to the traction wheels to propel the machine along the mine tracks 57.
- Auxiliary to the above described conveyor 60 I have provided a convenient means for moving the dislodged material over the floor of the mine and onto the conveyor, comprising a V-shaped scoop 73 to the diverging walls 74 of which there are attached bridle 65 chains 75. The bridle chains 75 are connected with a towing line 76, formed of a manila rope or other equally flexible material, by which said scoop may be drawn over the floor of the mine. At the rear end of the scoop there is provided a handle 77 for its 70 convenient manipulation.
- In the practice of my improved method of loading coal the machine above described is brought into the mine room and is positioned upon the mine tracks 57 near the working 75 face. The conveyor is then adjusted, as illustrated in Figs. 1 and 3, with its horizontal receiving portion resting upon the floor in convenient proximity to the material to be loaded. The apron which constitutes the inclined plane 14 is adjusted to its working position at that side of the conveyor towards the material which is to be loaded, and the pit car 67 is placed under the delivery end of the conveyor in position to receive the 80 coal therefrom. By the manipulation of the block 60 between the side sills 50 of the truck frame and the supplemental frame 58 the pivotal supporting member 63 may be so adjusted as to effect the adjustment of the 85 delivery end of the conveyor between the top of the pit car 67 and the roof of the mine to attain the most convenient proportioning of the available space for handling relatively 90 large fragments of coal and for distributing 95 the load in the car. A jack post 78, of a construction well known in mining machine practice, to which is attached a snatch block 79, is placed in position at the side of the conveyor opposite the inclined plane 14, and 100 securely anchored between the floor and roof of the mine.
- The scoop 73 is then carried away from the receiving portion of the conveyor, placed behind the loose material which is to be loaded, and the towing line 76 is passed around the snatch block 79 and given a few turns around the winch 39. When the motor 23 is started and tension is applied to the free end of the towing line 76 the scoop 105 73 will be drawn over the floor of the mine towards the conveyor and up the inclined plane 14 to move the material included between its flaring sides 74 onto the conveyor by which it will be quickly transferred to the pit car 67. The tension upon the free end of the towing line 76 is then released permitting the scoop 73 to be returned to the pile of loose material upon the mine 110 floor, and the operation may be repeated until the car 67 is entirely filled. When the material at one side, as for example the right hand side, of the conveyor is entirely 115 loaded the inclined plane apron 14 and the auxiliary side plate 19 will be transferred to opposite sides of the conveyor, the jack post 78 readjusted and the coal at the left hand side of the conveyor loaded in the manner above described. When the scoop 120 73 encounters a pile of material upon the 125 130

mine floor, or other similar obstruction, the tension of the towing line 76 tends to move the truck forwardly along the track, and I have provided extensions 7' at each side of the bottom plate 7 which may be engaged by the jack 78 to securely anchor the forward end of the conveyor in the preferred loading position, and thereby prevent movement of the machine during loading operation.

In order that the material loaded into the car 67 may be evenly distributed over its entire length said car is preferably placed close to the conveyor supporting truck to allow the first material loaded to fall into its rearmost end. A second towing line 80, having a hook 81 adapted to engage the end wall of the car, is placed in engagement with the winch 39 opposite that to which the tow line 76 is connected, and is passed over the guide sheave 82 mounted at the rear end of the conveyor frame. The hook 81 is then engaged with the forward end wall of the car 67 and, when tension is applied to the free end of the tow line 80 the car will be moved away from the machine. By properly manipulating the tow line 80 to move the car 67 in the manner above described, the material may be distributed to effect the proper trimming of the load. It is of course understood that the car may be moved either forwardly or backwardly according to which end wall is engaged by the hook 81. After the car 67 has been fully loaded it must be removed and another car placed in loading position under the delivery end of the conveyor, necessitating frequent interruptions of the loading operations. By the manipulation of the clutch 42" the conveyor chains 3 may be alternately stopped and started thereby moving the material delivered by the scoop 73 along the conveyor and accumulating a considerable mass of material thereon which can be quickly transferred to the car as soon as it is placed. By such manipulation suspension of the operation of the scoop is commonly entirely prevented and the efficiency of the machine very largely increased.

After the coal has been entirely loaded out of a room, the jack post 78 may be disengaged from the mine roof, the block 60 adjusted between the supplemental frame 58 and the side sills 22 of the conveyor raising the gathering end of the conveyor clear of the track rails 57. The apron 14 may be folded over onto the conveyor and the scoop, jack post and other accessories loaded onto the conveyor and the machine proceed to the next working place.

Due to the approximate equilibrium of the conveyor structure upon the hinge rod 62 the vertical adjustment of the conveyor can be accomplished by the miner's helper pressing downward or lifting upward upon the rearward end of the conveyor frame

while the miner himself adjusts the block 60 relative to the truck members to retain the parts in the desired working position.

What I claim is—

1. In a machine for loading coal in mines, the combination with a supporting truck, an elongated conveyor frame mounted upon said truck and adapted for adjustment in vertical planes whereby its receiving end may be placed in operative position in contact with the mine floor and may be elevated to traveling position, conveyor devices within the frame, and an apron hinged to said conveyor frame and adapted when in operative position to form an inclined plane over which material may be moved from the mine floor to the conveyor and which may be folded in traveling position upon the conveyor. 70
2. In a machine for loading coil in mines, the combination with a supporting truck, an elongated conveyor frame mounted upon said truck and adapted for adjustment in vertical planes whereby its receiving end may be placed in operative position in contact with the mine floor and may be elevated to traveling position, conveyor devices within the frame, and an apron hinged to said conveyor frame and adapted when in operative position to form a laterally extending inclined plane over which material may be moved from the mine floor to the conveyor and which may be folded in traveling position upon the conveyor.
3. In a machine for loading coal in mines, the combination with a supporting truck, of an elongated conveyor frame mounted upon said truck and adapted for adjustment in vertical planes whereby its receiving end may be placed in operative position in contact with the mine floor and may be elevated to traveling position, conveyor devices within the frame, and an apron removably hinged to said conveyor frame and adapted when in operative position to form a laterally extending inclined plane over which material may be moved from the mine floor to the conveyor and which may be folded in traveling position upon the conveyor. 110
4. In a machine for loading coal in mines, the combination with a supporting truck, an elongated conveyor frame mounted upon said truck and adapted for adjustment in vertical planes whereby its receiving end may be placed in operative position in contact with the mine floor and may be elevated to traveling position, conveyor devices within the frame, and an apron removable hinged to said conveyor frame and attachable at either side thereof and adapted when in operative position to form a laterally extending inclined plane over which material may be moved from the mine floor to the conveyor and which may be folded in traveling position upon the conveyor. 120
5. In a machine for loading coal in mines, 125

130

- the combination with a supporting truck, of an elongated conveyor frame mounted upon said truck and adapted for adjustment in vertical planes whereby its receiving end 5 may be placed in operative position in contact with the mine floor and may be elevated to traveling position, conveyor devices within the frame, power devices connected with said conveyor devices, a laterally extending 10 inclined plane attached to said conveyor frame, a scoop adapted to engage loose material upon the mine floor, a winch upon the conveyor frame connected with said power devices, a flexible draft member attached to 15 said scoop and windable upon said winch, and means to guide said draft member to cause said scoop to move said loose material over the mine floor and inclined plane onto 20 said conveyor.
- 20 6. In a machine for loading coal in mines, the combination with a wheeled truck adapted to travel over the mine tracks, a self contained conveyor comprising an elongated frame mounted upon said truck and adapted 25 for adjustment in vertical and horizontal planes whereby its receiving end may be placed in operative position in contact with the mine floor at either side of the mine track and may be elevated to traveling position 30 in the central plane of said track, conveyor and power devices within the frame, a laterally extending inclined plane attached to said conveyor frame, a scoop adapted to engage loose material upon the mine floor, a 35 winch upon the conveyor frame connected with said power devices, a flexible draft member attached to said scoop and windable upon said winch, and means to guide said draft member to cause said scoop to move said 40 loose material over the mine floor and inclined plane onto said conveyor.
7. In a machine for loading coal in mines, the combination of a support adapted to be moved over a mine floor, an elongated conveyor frame mounted on said support and having a floor engaging section, and an elevated car loading section, means for adjusting said frame vertically to bring its receiving end into contact with the mine floor and 45 into elevated position for transportation, conveying means carried by said frame, and a hinged apron detachably secured to the floor engaging end of said frame and extending lengthwise thereof a substantial distance to provide a shiftable and automatically adaptable incline for the delivery of gathered material to the conveyor at different points in its length.
- 50 8. In a machine for loading coal in mines, the combination of a support adapted to be moved over a mine floor, an elongated conveyor frame mounted on said support and having a floor engaging section, conveying means carried by said frame, and an apron 55 hinged to said frame and extending lengthwise thereof a substantial distance to provide an automatically adjustable incline for the delivery of gathered material to the conveyor at different points in its length.
- 55 9. In a machine for loading coal in mines, the combination of a support adapted to be moved over a mine floor, a conveyor frame mounted on said support and having a floor engaging section, apron supporting means on either side of said floor engaging section, and a detachable hinged apron adapted to be mounted on either side of said conveyor and extending lengthwise thereof a substantial distance to provide an automatically adjustable incline for the delivery of gathered material to the conveyor at different points in its length. 70
- 60 10. In a machine for loading coal in mines, the combination with a wheeled truck adapted to travel over the mine track, a self contained conveyor comprising an elongated frame supported upon said truck and extending rearwardly thereof, conveyor and power devices within said frame adapted to discharge material into a suitably positioned car beneath said frame extension, a winch upon said conveyor frame connected with said power devices, a flexible draft member windable upon said winch and attachable to 75 said car, and guide devices upon said frame extension adapted to guide said draft member to cause the movement of said car in the preferred direction relative to said truck. 80
- 80 11. In a machine for loading coal in mines, the combination of a support adapted to be moved over the floor of a mine, conveyor mechanism comprising an elongated frame mounted on said support and extending rearwardly thereof, conveyor and power devices carried by said frame and adapted to discharge material into a car from the rearwardly extending portion of said frame, winding means on said conveyor frame, driving connections between said winding means and said power devices, a flexible draft member engageable with said winding devices and adapted to be attached to a car, and guiding means for said draft member mounted on the rearwardly extending end of said 85 conveyor frame. 90
- 90 12. In a machine for loading coal in mines, the combination of a wheeled truck adapted to be moved over a mine track, a self-contained conveyor comprising an elongated frame mounted on said truck and having an elevated and rearwardly extending portion, conveyor and power devices carried by said frame and adapted to discharge material into a car beneath the elevated and rearwardly extending portion of said frame, a winding drum on said conveyor frame, driving connections between said winding drum and said power devices, a flexible draft member engageable at one end with said winding 95 100
- 100 13. In a machine for loading coal in mines, the combination of a support adapted to be moved over a mine floor, a conveyor frame having an elevated and rearwardly extending portion, conveyor and power devices carried by said frame and adapted to discharge material into a car beneath the elevated and rearwardly extending portion of said frame, a winding drum on said conveyor frame, driving connections between said winding drum and said power devices, a flexible draft member engageable at one end with said winding 105 110
- 110 14. In a machine for loading coal in mines, the combination of a support adapted to be moved over a mine floor, a conveyor frame having an elevated and rearwardly extending portion, conveyor and power devices carried by said frame and adapted to discharge material into a car beneath the elevated and rearwardly extending portion of said frame, a winding drum on said conveyor frame, driving connections between said winding drum and said power devices, a flexible draft member engageable at one end with said winding 115 120
- 120 15. In a machine for loading coal in mines, the combination of a support adapted to be moved over a mine floor, a conveyor frame having an elevated and rearwardly extending portion, conveyor and power devices carried by said frame and adapted to discharge material into a car beneath the elevated and rearwardly extending portion of said frame, a winding drum on said conveyor frame, driving connections between said winding drum and said power devices, a flexible draft member engageable at one end with said winding 125 130

- drum and adapted to be attached at its other end to a car, and a guide sheave for said draft member mounted at the end of said elevated and rearwardly extending frame 5 section.
13. In an apparatus for loading coal in mines, the combination with a self contained conveyor comprising an elongated frame having a substantially horizontal portion adapted to rest upon the mine floor, conveying and power devices within the frame, an apron adapted to be positioned at either side of said conveyor, and a material engaging scraper connected with the power devices of the conveyor adapted to propel loose material over the mine floor and apron onto the conveyor.
14. In an apparatus for loading coal in mines, the combination with a self contained 20 conveyor comprising an elongated frame having a substantially horizontal receiving section adapted to rest upon the mine floor, conveying and power devices within said frame, an apron adapted to be positioned at either side of said conveyor and connect- 25 85
- ible thereto by hinged supports, and a material engaging scraper connected with the power devices of the conveyor and adapted to propel loose material over the mine floor 30 and apron onto the conveyor.
15. In an apparatus for loading coal in mines, the combination with a self contained conveyor comprising an elongated frame and conveyor and power devices within the frame, a truck, a pivoted support upon said truck upon which said conveyor is supported for angular adjustment in both horizontal and vertical planes, and means to vertically 35 90
- adjust said pivotal support.
16. In a machine of the class described, the combination with a structure comprising an inclined elongated conveyor frame rigidly attached to a centrally disposed supporting frame which includes the center of gravity of the structure, of a conveyor mounted within said conveyor frame, power devices within said supporting frame arranged to actuate said conveyor, and a supporting truck comprising a vertically adjustable support- 40 95
- ing frame and a pivot member attached to said supporting frame and to said conveyor structure upon which said conveyor structure is angularly adjustable in both vertical and horizontal planes.
17. In a machine for loading coal in mines, the combination with a wheeled truck adapted to travel over the mine tracks, a self contained conveyor comprising an elongated frame supported upon said truck and extending rearwardly thereof, conveyor and power devices within said frame adapted to discharge material into a suitably positioned car beneath said frame extension, a scoop adapted to engage loose material upon the mine floor, a winch upon the conveyor frame 45 100
- connected with said power devices, a flexible draft member attached to said scoop and windable upon said winch to cause said scoop to propel said loose material onto said conveyor, and means to control the actuation 70 of the conveyor independently of the other elements of the machine.
18. In a machine for loading coal in mines, the combination with a supporting truck, of an elongated conveyor frame mounted upon said truck, conveyor devices within the frame, power devices connected with said conveyor devices, a scoop adapted to engage loose material upon the mine floor, a winch upon the conveyor frame connected with 75 105
- said power devices, a flexible draft member attached to said scoop and windable upon said winch, anchoring devices adapted to prevent movement of the conveyor relative to the material to be loaded, and guiding devices associated with said anchoring devices adapted to engage said flexible draft member to cause said scoop to move said loose material over the mine floor and onto the conveyor.
19. In a machine for loading coal in mines, the combination with a supporting truck, of an elongated frame mounted upon said truck and adapted for adjustment in vertical planes whereby its receiving end may be placed in operative position in contact with the mine floor and may be elevated to traveling position, conveyor devices within the frame, power devices connected with said conveyor devices, a scoop adapted to engage loose material upon the mine floor, a winch upon the conveyor frame connected with said power devices, a flexible draft member attached to said scoop and windable upon said winch, and means to guide said draft member to cause said scoop to move said loose material over the mine floor onto said conveyor.
20. In a machine for loading coal in mines, the combination with a wheeled truck adapted to travel over the mine tracks, a self contained conveyor comprising an elongated frame mounted upon said truck and adapted for adjustment in vertical and horizontal planes whereby its receiving end may be placed in operative position in contact with the mine floor at either side of the mine track and may be elevated to traveling position in the central plane of said truck, conveyor and power devices within the frame, a scoop adapted to engage loose material upon the mine floor, a winch upon the conveyor frame connected with said power devices, a flexible draft member attached to said scoop and windable upon said winch, and means to guide said draft member to cause said scoop to move said loose material over the mine floor onto said conveyor.
21. In a machine of the class described, the combination with a structure comprising 110 115 120 125 130

an inclined elongated conveyor frame rigidly attached to a centrally disposed supporting frame which includes the center of gravity of the structure, of a conveyor mounted within said conveyor frame, power devices within said supporting frame arranged to actuate said conveyor, a truck having a pivotal supporting member which is attached to said supporting frame adjacent to and in the rear of said center of gravity, upon which said conveyor structure is rotatably supported.

22. In a machine of the class described, the combination with a structure comprising an inclined elongated conveyor frame rigidly attached to a supporting frame which includes the center of gravity of the structure, of a conveyor mounted within the conveyor frame, power devices within said supporting frame and arranged to actuate said conveyor, a supporting truck having a pivotal supporting member which is attached to said supporting frame adjacent to and in the rear of said center of gravity upon which said structure is rotatably adjustable in vertical planes.

23. In a machine for loading coal in mines, the combination with a wheeled truck, of a bolster adapted for rocking movement about a horizontal axis extending transversely of said truck, and an elongated conveyor frame supported upon said bolster and adapted for angular horizontal adjustment about a vertical axis extending through said bolster.

24. In a machine for loading coal in mines, the combination with a wheeled truck, of a bolster adapted for rocking movement about a horizontal axis extending transversely of said truck and vertically adjustable relative thereto, an elongated conveyor frame supported upon said bolster and adapted for angular horizontal adjustment about a vertical axis extending through said bolster.

25. In a machine for loading coal in mines, the combination with a wheeled truck, of a bolster extending transversely of said truck, and vertically adjustable relative thereto, an elongated conveyor frame supported upon said bolster and adapted for angular horizontal adjustment about a vertical axis extending through said bolster.

26. In a machine for loading coal in mines, the combination of a support adapted to be moved over a mine floor, a conveyor frame so mounted on said support that its center of gravity is substantially in line with the center of gravity of the support, a means connecting said frame and support to permit relative vertical adjustment, and a connecting means to permit relative horizontal adjustment.

27. In a machine for loading coal in mines, the combination of a support adapted to be moved over a mine floor, a conveyor frame mounted on said support, means for

adjusting said frame vertically relative to said support, a rocking connection between said parts to permit tilting of said frame, and a connection between said frame and said adjusting means to permit angular adjustment of said frame in a horizontal plane.

28. In a machine for loading coal in mines, the combination with a support, of a conveyor frame, a supporting frame between said conveyor frame and said support pivotally connected at one end to said support, and a pivotal connection between said supporting frame and said conveyor frame.

29. In a machine for loading coal in mines, the combination with a support, of a conveyor frame, a supporting frame between said conveyor frame and said support pivotally connected at one end to said support, a horizontally disposed pivot element connecting said conveyor frame with said supporting frame, and a vertically disposed pivotal connection between said conveyor frame and said pivot element.

30. In a machine for loading coal in mines, the combination of a support, a conveyor frame, and an intermediate frame pivotally connected at one end to said support and having a vertically disposed pivotal connection with said conveyor frame at a point removed from its pivotal connection with said support.

31. In a machine for loading coal in mines, the combination of a support, a conveyor frame, a lazy tong connection between said support and said conveyor frame, and a vertically disposed pivotal connection between said conveyor frame and said lazy tong element to permit horizontal angular adjustment of said conveyor frame relative to said support.

32. In a machine of the class described, an elongated conveyor frame and draft devices operable therealong, an under supporting frame rigidly connected to said conveyor frame intermediate the ends of the latter, motive means for said draft devices disposed in said supporting frame, a truck, and a pivotal connection between said supporting frame and said truck.

33. In a machine of the class described, an elongated conveyor frame and draft devices operable therealong, an under supporting frame rigidly connected to said conveyor frame intermediate the ends of the latter, motive means for said draft devices housed in said supporting frame, a truck, and pivotal connections between said supporting frame and said truck to permit horizontal and vertical swinging movement of the conveyor frame relative to said truck. 115

34. In a machine of the class described, an elongated conveyor frame and draft devices operable therealong, an under supporting frame rigidly secured to said conveyor frame and including the center of gravity of the 120 125 130

latter, motive means for said draft devices disposed in said supporting frame, and a pivotal connection between said supporting frame and said truck to the rear of said center of gravity.

35. In a machine of the class described, an elongated conveyor frame and draft devices operable therealong, an under supporting frame rigidly secured to said conveyor frame

and including the center of gravity of the 10 latter, motive means for said draft devices disposed in said supporting frame, a truck, and pivotal connections between said supporting frame and said truck to permit horizontal and vertical swinging movements of the conveyor frame relative to the truck.

In testimony whereof, I affix my signature
NILS D. LEVIN

latter, motive means for said draft devices disposed in said supporting frame, and a pivotal connection between said supporting frame and said truck to the rear of said center of gravity.

35. In a machine of the class described, an elongated conveyor frame and draft devices operable therealong, an under supporting frame rigidly secured to said conveyor frame

and including the center of gravity of the 10 latter, motive means for said draft devices disposed in said supporting frame, a truck, and pivotal connections between said supporting frame and said truck to permit horizontal and vertical swinging movements of the conveyor frame relative to the truck.

Certificate of Correction.

Patent No. 1,645,653.

Granted October 18, 1927, to

NILS D. LEVIN.

It is hereby certified that error appears in the printed specification of the above-numbered patent requiring correction as follows: Page 1, line 81, strike out the words "gated trough composed of" and insert instead *cross bars 4. Attached to*; page 4, line 84, claim 2, for the word "coil" read *coal*; same page, line 122, claim 4, for the word "removable" read *removably*; and that the said Letters Patent should be read with these corrections therein that the same may conform to the record of the case in the Patent Office.

Signed and sealed this 17th day of January, A. D. 1928.

[SEAL.]

M. J. MOORE,
Acting Commissioner of Patents.
